(57) CLAIM

The ornamental design for a picture frame, as shown and described.

DESCRIPTION

FIG. 1 is a top, front and right side perspective view of a picture frame, showing my new design;
FIG. 2 is a bottom, rear and left side perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is an enlarged view of portion 9 in FIG. 1; and,
FIG. 10 is an enlarged view of portion 10 in FIG. 2.
The evenly broken lines show the features of the picture frame that form no part of the claimed design. The unevenly broken lines define the boundaries of the enlarged views that form no part of the claimed design.

1 Claim, 10 Drawing Sheets
